UNITED STATES PATENT OFFICE

134,176

DESIGN FOR A PHOTOELECTRIC CELL

Anthony H. Lamb, Hillside, N. J., assignor to
Weston Electrical Instrument Corporation,
Newark, N. J., a corporation of New Jersey

Application August 18, 1942, Serial No. 107,958

Term of patent 14 years

To all whom it may concern:

Be it known that I, Anthony H. Lamb, a citizen of the United States of America, residing at Hillside, county of Union, State of New Jersey, have invented a new, original, and ornamental Design for a Photoelectric Cell, of which the following is a specification, reference being had to the accompanying drawing, forming part thereof, and wherein:

Fig. 1 is a face view of the photoelectric cell showing my new design;

Fig. 2 is a side elevation of the same; and

Fig. 3 is a rear view of the photoelectric cell.

I claim:

The ornamental design for a photoelectric cell, as shown.

ANTHONY H. LAMB.
